UNITED STATES PATENT OFFICE.

CHARLES J. BRINKMANN, OF GLENCOE, MINNESOTA.

AUTOMOBILE-HORN.

1,105,615.

Specification of Letters Patent.

Patented Aug. 4, 1914.

Application filed November 1, 1913. Serial No. 798,731.

To all whom it may concern:

Be it known that I, CHARLES J. BRINKMANN, a citizen of the United States, residing at Glencoe, in the county of McLeod and State of Minnesota, have invented certain new and useful Improvements in Automobile-Horns, of which the following is a specification, reference being had to the accompanying drawings.

10 This invention comprehends certain new and useful improvements in automobile horns and has for its primary object to provide a device of this character including a plurality of tubes secured at their outer ends to a central support and having their inner ends with the inner end of the central support secured to a head adapted to be connected with the exhaust port of the automobile engine, said inner ends of the tubes being formed in such manner as to give an audible signal when the exhaust gases pass through the same to the surrounding atmosphere.

25 Another object is to provide a device of this character including air vents having cylindrical inner ends tapped into the head while the inner ends of the resonant tubes are split and engaged around the flattened outer ends of the air vents, said tubes having air escape openings at the outer ends of the air vents with wings to opposite sides and straight flattened outer edges against which the exhaust gases from the muffler will impinge as they pass out of the discharge or outer ends of the air vent, and sound a note of a different pitch in each tube, as will be readily understood.

30 A further object is to generally improve and simplify the construction of devices of this character and increase the efficiency of the same and at the same time decrease the cost of manufacture of the device.

35 With the above and other objects in view, my invention consists in certain novel constructions, combinations, and arrangements of parts to be hereinafter more fully described, claimed, and illustrated in the accompanying drawings, in which,

40 Figure 1 is a perspective view of the complete device; Fig. 2 is a transverse sectional view through the head 4, looking toward the outer end of the device, the resonant tubes being removed; Fig. 3 is a transverse sectional view through the central support outwardly of the air vents, looking inwardly toward the head, the resonant tubes being

removed. Fig. 4 is an enlarged detail perspective view of the inner end of one of the pipes, and the air vent carried thereby; and Fig. 5 is an enlarged detail fragmentary sectional view, showing the manner in which the outer ends of the tubes are secured upon the central support.

45 Referring more specifically to the drawings in which similar reference characters designate corresponding parts throughout the several views, 1 designates the central support around which are positioned the resonant tubes 2, which tubes are spaced in parallel relation to the central support 1 50 and surround the same, said tubes being secured at their outer ends to said central support 1, by co-acting laterally projecting slip-joint members 3 and 3'.

55 The inner end of the central support 1 and the inner ends of the tubes 2 are tapped into the head 4. The inner end of the central support 1 is tapped into the head 4 while the inner ends of the resonant tubes 2 are engaged against the head 4 and reduced, said reduced inner ends of the tubes 2 being split longitudinally and engaged around the outer flattened ends of the air vents 5, as shown at 6. The inner ends of the air vents 5 are of cylindrical form and 60 tapped into the head 4 around the inner end of the central support 1 and outwardly of the same, as will be readily understood by referring to the drawings.

65 The tubes 2, as will be understood, are of different lengths and have the air escape openings 7 formed in their outer faces at the outer or discharge ends of the air vents 5, the side walls of each air escape opening being extended outwardly and parallel to 70 one another to form wings 8, while the wall of the air escape opening opposite the discharge end of the air vent is flattened, whereby a straight edge 9 is provided against which the exhaust gases from the muffler 75 will impinge as they pass out of the discharge end of the air vent and said air vents are so arranged that said exhaust gases will strike exactly at the straight edge 9 and sound a note of a different pitch in each 80 tube 2.

85 The space between the lower face of the flattened outer end of each vent and the opposite portion of the inner wall of the resonant tube 2, from the outer or discharge 90 end of said air vent to the adjacent wall of the head 4, is filled with a suitable material,

such as plaster Paris, the purpose of which will readily appear.

Each slip joint consists of a laterally projecting member 3 carried by the central support 1 and a laterally directed socket member 3' carried by one of the pipes 2 and as these slip joint members are preferably formed of soft metal, the socket member will not readily become disengaged from the laterally projecting member. The slip joints may be readily fastened on the outer ends of the pipes and disengaged completely from the central support 1, when the pipes are being secured to the air vents 5 or removed from the same. It will be seen that while the inner end of one pipe is being secured to the air vent for the same or disengaged from said air vent, the remaining pipes will be readily held in position by the slip joint members 3 and 3'.

From the foregoing, it will be clearly apparent that I have provided an automobile horn of extremely simple and cheap construction and which will be highly efficient and effective in use. It will also be readily seen that owing to the manner in which each resonant tube is independently secured to and spaced from the central support and has its reduced inner end secured around the outer flattened end of the air vent provided for the same and tapped into the head, each tube may be readily secured in position or removed without disturbing the other tube or tubes. It will further be seen that while I have shown the preferred embodiment of the device, I do not wish to be limited to the same, as minor changes in the details of construction may be made within the scope of the appended claims without departing from the spirit of my invention

or sacrificing any of the advantages of the same. It will also be seen that while I have shown the device as including five resonant tubes, any suitable number may be employed.

What I claim is:—

1. A device of the class described comprising a head, a plurality of air vents detachably mounted in said head and projecting therefrom, a central support projecting from the head, a plurality of resonant tubes, each of said tubes having an air escape opening formed therein adjacent its inner end, each tube being split longitudinally from the inner wall of the opening therein to the inner edge of the tube to provide a pair of wings, the split portion of each tube being adapted for slidable engagement with the projecting end of one of said air vents, and means for loosely connecting the outer end of each tube to the central support.

2. A device of the class described comprising a head, a central support projecting from the head, a plurality of resonant tubes, a plurality of air vents carried by the head and having reduced extended portions, the inner end of each tube being engaged around the extended portion of one of said air vents, a plurality of laterally projecting slip joint members carried by the central support, and a laterally projecting slip joint socket member carried by the outer end of each tube and adapted for engagement with one of said laterally projecting slip joint members carried by the central support.

In testimony whereof I hereunto affix my signature in the presence of two witnesses.

CHARLES J. BRINKMANN.
